UNITED STATES PATENT OFFICE

161,590

CIGARETTE AND BOOK MATCH DISPENSER

Frederic O. Pattison, Jr., Seattle, Wash.

Application February 10, 1950, Serial No. 7,875

Term of patent 3½ years

(Cl. D52—2)

To all whom it may concern:

Be it known that Frederic O. Pattison, Jr., a citizen of the United States, residing at Seattle, Washington, has invented a new, original, and ornamental Design for a Cigarette and Book Match Dispenser, of which the following is a specification, reference being had to the accompanying drawing, forming a part thereof, in which:

Figure 1 is a perspective view of a cigarette and book match dispenser embodying my new design;

I claim:

The ornamental design for a cigarette and book match dispenser, as shown.

FREDERIC O. PATTISON, JR.
